CHIMNEY CLEANER

Joseph R. Puett, Prairie City, Oreg.

Application April 30, 1954, Serial No. 426,630

2 Claims. (Cl. 15—243)

This invention comprises novel and useful improvements in a chimney cleaner and more specifically pertains to a device for cleaning chimneys by scraping the same.

The primary object of this invention is to provide an improved chimney cleaner which may be easily and readily manipulated by the householder for effectively cleansing his chimneys.

A further object of the invention is to provide a chimney cleaner in conformity with the preceding object wherein the device may be readily adjustable to effectively clean chimneys of different sizes.

A still further object of this invention is to provide an apparatus as set forth in the above mentioned objects, wherein a scraping and sweeping operation may be simultaneously effected if desired.

These, together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view showing the chimney cleaner in accordance with this invention, the same having a pair of cleaning elements adapted to scrape both sides of a chimney;

Figure 2 is a horizontal sectional view through a portion of a chimney showing the manner in which the apparatus of Figure 1 is operatively disposed therein for scraping the walls of a chimney, and

Figure 3 is a vertical transverse sectional view of a chimney and showing the manner in which the scraper of Figure 1 is operably associated therewith.

In the accompanying drawings, the novel chimney sweeper in accordance with this invention consists of an H-frame indicated generally by the numeral 10 and to which a handle 12 is secured having at its upper end a ring 14 by which a cable or chain may be attached for vertically reciprocating the device within a chimney indicated by the numeral 16 in Figures 2, 3, 5 and 6.

The H-frame comprises a pair of bars constituting elongated arms 18 and 20 and which originally connect at their midportions by a cross bar 22. If desired, the arms and the cross bar may be of integral construction. The opposite ends of each arm are provided with elongated slots 24 by means of which cleaning elements as set forth hereinafter are adjustably secured to and mounted upon the H-frame for reciprocation therewith.

Referring now specifically to Figures 1-3, it will be seen that the cleaners may comprise an elongated body 26 adapted to extend across the adjacent ends of a pair of arms and to be adjustably secured thereto by means of bolts 28 which extend through the pair of slots 24 and into the bodies 26. By means of these bolts the bodies may be adjusted towards and from each other upon the H-frame, whereby the cleaning elements carried by the bodies may be adjusted to engage the opposite walls of chimneys of different size.

The cleaner element disclosed is specifically adapted for the function of scraping scale or other heavy deposits from the walls of the chimney flue, and for yield-

2

ingly conforming to the contour of the flue to permit easy passage of the cleaning device therethrough. For this purpose, there is provided a stiff spiral spring 30, constituting a resilient scraping element and which is 5 adapted to engage against the walls of the flue as shown in Figure 2. This spring is resiliently and yieldingly supported from the body by means of a plurality of coil springs, and preferably there is provided a coil spring 32 at each end of the scraper spring 30 and the central 10 stiffening supporting spring 34 intermediate the ends of the spring 30. These coil springs 32, 34 are suitably mounted upon and carried by the body 26 in any desired manner.

It will thus be evident that the scraper 30 will be 15 resiliently held against the wall of the chimney flue in a manner which will permit the scraper to conform to irregularities in the flue and thus insure passage of the scraper therethrough, but which will cause the scraper to stiffly engage and effectively scrape and cleanse the 20 wall of the flue. By adjusting either of the cleaner elements, as by adjusting one of the bodies 26, the spacing between the scraping edges of the two elements may be 25 varied to cause the same to compensate for different sizes of chimneys. Alternately, of course, both cleaner elements may be simultaneously adjusted. It will thus be seen that the tool is readily adjusted and varied to cause the same to accommodate itself most effectively to different sizes of flues.

The device especially lends itself to economical light 30 weight construction, but is extremely durable, readily adjustable to fit different sizes of chimneys and easily used by the householder.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A chimney cleaning device comprising a horizontal H-shaped frame having a pair of parallel coplanar side arms with a crossbar rigidly joined to their midportions, a pair of cross members traversing said side arms at opposite sides of said crossbar and slidably connected to said side arms below the same for adjustment laterally along said side arms, and a helical scraper spring extending from each opposite end of each cross member outwardly beyond said side arms, said springs having corresponding ends connected to said cross members and being free from their connected ends outwardly for vertical flexing, and a helical scraper spring cross-connecting the outer ends of each pair of similarly extending scraper springs with ends attached thereto and being free between its attached ends for flexing.

2. The combination of claim 1, and a helical spring extending from each cross member to the corresponding cross-connecting spring and lying between the similarly extending pair of helical springs with ends attached to the member and to the cross-connecting spring.
